United States Patent Office

Des. 213,715
Patented Apr. 1, 1969

213,715

GRIDDLE

George T. Scharfenberg, 7601 Wayzata Blvd.,
Minneapolis, Minn. 55426

Filed June 12, 1968, Ser. No. 12,310

Term of patent 14 years

Int. Cl. D7—02

U.S. Cl. D44—1

FIG. 1

FIG. 2

FIG. 3

FIG. 4

FIG. 5

FIG. 7

FIG. 1 is a perspective view of a griddle showing my new design;

FIG. 2 is a rear elevational view;
 FIG. 3 is a top plan view;
 FIG. 4 is a left end elevational view;
 FIG. 5 is a right end elevational view;
 FIG. 6 is a front elevational view;
 FIG. 7 is an enlarged scale sectional view taken on line 7—7 of FIG. 6;
 FIG. 8 is a top plan view in open condition; and
 FIG. 9 is an enlarged scale sectional view taken on line 9—9 of FIG. 8.

I claim:

The ornamental design for a griddle, as shown.
